(57) **CLAIM**

The ornamental design for a wine bottle drinking accessory, as shown and described.

DESCRIPTION

FIG. 1 is a front perspective view of a wine bottle drinking accessory showing our new design;

FIG. 2 is a front view thereof; the rear view, right side view, and left side view being a mirror image thereof;

FIG. 3 is a top view thereof;

FIG. 4 is a bottom view thereof; and,

FIG. 5 is an environmental perspective view thereof.

The broken lines in the drawing depict environmental subject matter only and form no part of the claimed design.
